UNITED STATES PATENT OFFICE.

JACOB M. HARRIS, OF NEW YORK, N. Y., ASSIGNOR TO FULTON BELL COMPANY, OF NEW YORK, N. Y., A CORPORATION OF NEW YORK.

TOASTER.

Application filed January 30, 1923. Serial No. 615,872.

To all whom it may concern:

Be it known that I, JACOB M. HARRIS, a citizen of the United States, residing in the city of New York, county of Kings, and 5 State of New York, have invented a certain new and useful Improvement in Toasters, of which the following is a specification.

My invention relates to vertical toasters in which a central heating element is 10 disposed between toast supporting grids against which the slices of bread rest while being toasted. In such toasters it has been common practice to have doors hinged at the lower edges at the bottom of the toaster, 15 adapted when in their closed position to hold the toast against the grid and in their open position to form a tray into which the toast may fall. It has further been customary to have some kind of a toast support 20 attached to the lower part of the door so that when the door is opened the toast is automatically and by that same motion dumped into the tray, generally in such a way as to cause the toast to be reversed when it is 25 again applied to the grid by restoring the door to its closed position.

I have found that it is not always desirable to have the toast dumped simultaneously with the opening of the door. In my 30 present invention I have arranged a combination of devices whereby the toast rests on a pivoted support independent of the door, the independent support having a handle of its own for retracting the same and 35 dumping the toast and a spring of its own for returning the support to its normal toast supporting position.

In the accompanying drawings which 40 form part of this specification—

Fig. 1 represents a vertical transverse section of a toaster embodying my invention;

Fig. 2 a side elevation of the same with a door lowered;

Fig. 3 represents a transverse section of 45 another form that my invention may take; and

Fig. 4 a side elevation of the same with one door lowered.

1 may represent a suitable base upon 50 which is mounted a framework 2 having a top 3. The heater element is shown at 4 and is supported by a framework 5 and connected with electric terminals 6. Grids 7 are mounted on a frame in planes approximately parallel to the heater element. Piv-

oted at 8 at the lower edges are hinged doors 9 which can be pulled down in the lowered position by handles 10, while springs 11 tend to restore them to their vertical position. Between the lower edges of the doors and the lower parts of the grids are interposed 60 toast supports 12 which may be in the form of rollers as shown in Figs. 1 and 2. Such a roller is provided with handles 13, by which it may be turned in a direction away from the grid so as to dump the toast supported on it while a spring 14 serves to return the roller to its normal position. A pin 15, fastened to the roller impinging against a stop 16 limits the backward throw 70 of the roller.

The toast support may be in the form of a rocking plate 17 as shown in Figs. 3 and 4, which plate may have ears 18 through which a pivot shaft 19 may pass to form a hinge. 75 A stop 20 will limit the toast support in its backward swing under the action of the spring 21, and a handle 22 may provide means whereby the toast support can be rocked forward so as to dump the toast on 80 to the door 9 when the latter is in its lowered position.

By a combination of this kind there is produced a toaster having greater variability of operation than those heretofore made 85 and I therefore claim:—

1. A vertical toaster comprising a grid approximately vertical, a door hinged at its lower edge and adapted to hold the toast against the grid when in its closed position 90 and to form a tray for receiving the toast in its open position and a toast support pivoted independently of the door between the door and the grid and adapted to roll the lower end of the toast outwardly so as 95 to dump the toast on to the opened door.

2. The combination in a toaster having a vertical grid, a door hinged at the bottom and a rocking pivoted toast support independent of the door between the door and the grid, a spring tending to hold the said toast support against a fixed stop and a handle for retracting the support against the action of the spring for dumping the toast. 100

3. A vertical toaster comprising in combination a grid approximately vertical, a spring closed door hinged at its lower end for holding the toast against the grid when in its closed position and for catching the 110

toast when in its open position and a spring actuated roller toast support between the grid and the door for supporting the toast independently of the door and adapted 5 when rolled back to dump the toast on to the door.

4. A vertical toaster comprising in combination a grid approximately vertical, a spring closed door hinged at its lower end 10 for holding the toast against the grid when in its closed position and for catching the toast when in its open position and a spring actuated roller toast support between the grid and the door for supporting the toast 15 independently of the door and adapted when rolled back to dump the toast on to the door,

both door and roller having operating handles.

5. A vertical toaster comprising a grid approximately vertical, a door hinged at its lower edge for holding the toast against the grid when in its closed position and for catching the toast when in its open position, a toast-support independent of the door and located between the grid and the door, and means operable independently of the door for moving the lower edge of the toast outwardly from the toast-support to permit it to slide upon the open door for the purpose of reversing the same. 20 25
